CLAIM

The ornamental design for a radiating repeater case, as shown and described.

DESCRIPTION

FIG. 1 is a front perspective view of a repeater case incorporating a design according to the invention.

FIG. 2 is a front view of the repeater case of FIG. 1.

FIG. 3 is a right side view of the repeater case of FIG. 1.

FIG. 4 is a left side view of the repeater case of FIG. 1.

FIG. 5 is a back view of the repeater case of FIG. 1.

FIG. 6 is a top view of the repeater case of FIG. 1; and,

FIG. 7 is a bottom view of the repeater case of FIG. 1.
